PUMPING APPARATUS

Alexander D. Ferguson, Michigan City, Ind., assignor to Sullivan Machinery Company, a corporation of Massachusetts

Application December 31, 1935, Serial No. 56,977

6 Claims. (Cl. 230—58)

My invention relates to pumping apparatus, and more particularly to improved driving means for pumping apparatus.

For the purpose of conserving space, it is desirable to mount the driving motor for pumping apparatus in a position in which a minimum of floor space will be required, and for this purpose superposing the driving motor with respect to the pumping apparatus is quite advantageous.

It is an object of my invention to provide an improved pumping apparatus including a pumping device and a driving motor therefor, arranged in an improved manner. It is another object of my invention to provide improved mounting for the driving motor for pumping apparatus, whereby the driving motor may be mounted on a conventional pumping device with a minimum of change and with provision for the convenient adjustment of the driving element of the motor relative to the driven element of the pumping device, so as to obtain the most effective driving relation. A further object of my invention is to provide an improved motor support. Other objects and advantages of my invention will herein-after more fully appear.

In the accompanying drawing, in which one embodiment which my invention may assume in practice has been shown for purposes of illustration,—

Fig. 1 is a side elevation of a pumping apparatus in which the invention is embodied;

Fig. 2 is a sectional view on the plane of the section line 2—2 of Fig. 1;

Fig. 3 is a fragmentary vertical section on a plane corresponding to the line 3—3 of Fig. 2.

Referring to the drawing, it will be observed that a pumping apparatus 1, herein shown as an air compressor, is provided with a suitable base and crank case 2, and cylinder 3, the latter being supported by the combined base and crank case. The compressor has a combined flywheel and driving pulley 4 mounted upon its crank shaft 5. The crank case and base 2 is provided with a projecting portion 6 providing a flange 7, and the cylinder proper 8 and cylinder head 9 are adapted to be held to the flange 7 by appropriate threaded rods or studs 10 and nuts 11. A driving motor 12 having a driving pulley 13 connected by a driving belt 14 to the combined flywheel and driving pulley 4 of the pumping device, is supported in an improved manner by the pumping apparatus. It will be observed that the motor 12 is suitably held, as by screws 15, to a platform 16 whose end nearer the crank shaft 5 is adjustable upwardly and downwardly by a screw 17,

which is held in adjusted position by a lock nut 18. Adjustment of the platform 16 is provided for by its pivotal mounting at 19 on an improved support member 20, which is herein in the form of an annulus 21 having upstanding lugs or brackets 22 thereon terminating in eyes 23 through which the pivot rod 24 passes, the pivot rod 24 also passing through depending brackets 25 on the base 16. It will be observed that the annular portion 21 is traversed by a series of 10 holes 26 formed to permit the passage therethrough of the threaded holding elements 10, and that the member 20 is clamped by the holding elements 10 between the collar 7 on the base and crank case 2 and the cylinder head 9, the parts 15 being rigidly connected together and all held in assembled relation by the common holding means including the threaded members 10 and the nuts 11.

It will be evident that this device provides for 20 an extremely compact construction; that a minimum departure from standard pumping apparatus construction is necessary; that additional holding elements are not required; and that the overall dimension of the machine is increased but 25 slightly with the apparatus shown, and with a wider pumping apparatus would not be increased any more than by the thickness of the member 20. It will be observed that by the adjusting means 17, 18 and the pivotal support 16, the most 30 advantageous belt tension may be secured; and it will further be appreciated that the entire device is of the utmost simplicity of construction.

While I have in this application specifically described one form which my invention may assume 35 in practice, it will be understood that this form is shown for purposes of illustration and that the invention may be modified and embodied in various other forms without departing from its spirit or the scope of the appended claims.

What I claim as new and desire to secure by Letters Patent is:

1. In combination, a pumping device including a base, a cylinder member, a cylinder head member, devices for clamping the same together, and 45 a driving pulley, and driving means for said pumping device including a driving motor having a mounting including a member held by said clamping devices, a platform pivotally connected to said last mentioned member, and means for adjusting said platform to change the relation of said motor to said driving pulley.

2. In combination, a pump including a driving element, a frame, and a pump cylinder, a motor for driving said pump driving element, a detach- 55

- able support interposed between said frame and said cylinder, and means for pivotally mounting said motor on said support in a position overlying said pump.
5. In combination, a pumping device including a base, a cylinder member, a cylinder head member, devices for clamping the same together, and a driving pulley, a driving motor operatively connected with said driving pulley, and motor supporting means including a member held by said clamping devices.
6. In combination, a pumping device including a base member, a cylinder member, and a driving element, a driving motor operatively connected to drive said driving element, and motor supporting means including an element clamped between the cylinder and base members and an element supported in part by said clamped element and in part by one of said members only.
5. In combination, a pumping device including a pump cylinder, a piston within said cylinder and a pump cylinder head, said piston having a piston rod reciprocable through said head, and means for clamping said cylinder and cylinder head together, a driving motor for said pumping device, and a supporting device for said motor positioned by said clamping means.
6. In combination, a pumping device including a pump cylinder, a piston reciprocable within said cylinder and a pump cylinder head, said piston having a reciprocable actuating connection extending through said head, and means for clamping said cylinder and cylinder head together, a driving motor for said pumping device, and a supporting device for said motor positioned by said clamping means and surrounding said reciprocable actuating connection.

ALEXANDER D. FERGUSON.
